UNITED STATES PATENT OFFICE.

NICHOLAS STRAUSSLER, OF LONDON, ENGLAND.

SILENCER FOR GASEOUS CURRENTS.

Application filed June 3, 1925. Serial No. 34,536.

To all whom it may concern:

Be it known that I, NICHOLAS STRAUSSLER, a Rumanian subject, residing at 32 St. Swithin's Lane, London, in the county of London, England, have invented certain new and useful Improvements in or Relating to Silencers for Gaseous Currents, of which the following is a specification.

This invention relates to silencers for 10 gaseous currents, such as are produced in the exhaust of internal combustion engines. Such a silencer as already known comprised a transversely divisible silencer body or casing into which was fitted a filling consisting of a permeable homogeneous mass of metal of a resilient character, such as very 15 narrow and thin twisted strips of flexible metal enclosed in a reticulated metal bag, and tapered ribs were provided at the inlet 20 end of the said body or casing to divert a portion of the incoming gases to the sides of the filling.

According to the present invention the filling is enclosed between two perforated 25 paraboloidal, conical or similarly shaped steel shells or interior casings, which may be secured in position by means of annular enlargements fitting into sockets or recesses formed at the meeting ends of the sections 30 of the silencer body or outer casing and dividing the latter into two chambers so that the exhaust gases entering one of said chambers have to pass through the perforated casings and filling to reach the other 35 chamber. These perforated casings prevent the filling from being compressed towards the silencer outlet by the impact of the entering gases. As the cross-sectional area of the space between the inner and outer 40 casings is reduced from each end towards the middle of the silencer by reason of the curve or taper of the inner casing, the aforesaid ribs on the outer casing, which were somewhat difficult to keep clean, can 45 be omitted, and the gases will enter the filling longitudinally and radially. The total area of the perforations in one inner casing may be larger than the area of the inlet, so that a certain degree of carbon 50 deposition will not choke the gas passages, and the perforations may be arranged in several circumferential rows in each section of the inner casing, in order to avoid any 55 tendency of the gases to take an unduly short path through the filling. The rows of

perforations are preferably confined to the central part of each shell or inner casing, that is, a broad band of its surface adjacent to the socket is not perforated, and the nose of the shell is also imperforate. The inner 60 casings can be readily withdrawn and separated from the filling.

In order that the said invention may be clearly understood and readily carried into effect, the same will now be described more 65 fully with reference to the accompanying drawing, which represents in longitudinal section a silencer body, fitted with two conical shells or inner casings, one of the said conical shells being also represented in section. 70

A and B indicate respectively the two halves or sections of a divisible silencer body, secured together by a metal clip or band C which can be tightened by means 75 of a bolt and wing-nut or the like; D and E indicate respectively the two shells or inner casings, and F the filling. The shells are perforated as shown at G, and have at their bases flanges or annular enlargements d', e' 80 fitting into the socket formed by the flanged meeting ends of the sections A and B. The section A may have a projecting ferrule or reduced portion a' which can be secured to the exhaust pipe of an internal combustion 85 engine, and the section B can be detached when it is required to withdraw and replace the filling, which can be taken out along with one or both of the shells D, E.

What I claim and desire to secure by Letters Patent of the United States is:—

1. A silencer comprising an outer casing transversely divisible into sections, the meeting portions of which sections form sockets, an inner casing also transversely divisible 95 into two approximately conical shells each having at its base an annular enlargement to fit into one of said sockets, each of said shells being perforated with a number of circumferentially arranged perforations located only in the part of said shell intermediate between its base and its apex, and filling consisting of a permeable homogeneous mass of metal of a resilient character enclosed within said inner casing. 100

2. A silencer comprising an outer casing having an inlet opening and an outlet opening, an inner casing containing filling material mounted within the outer casing with a wall thereof spaced from the outer casing 110

between the inlet and outlet openings, said inner casing having a substantially imperforate portion at one end which is adapted to deflect a fluid after it passes through the inlet opening so that it contacts with the wall, said wall being perforated to permit the passage of the fluid into the inner casing, and means arranged intermediate the ends of the inner casing for obstructing the space between the outer casing and the said wall of the inner casing to cause the fluid to pass into the inner casing before it passes through said outlet opening.

3. A silencer comprising an outer casing having an inlet opening and an outlet opening, an inner casing containing a filling material mounted within the outer casing with a wall thereof spaced from the outer casing between the inlet and outlet openings, said inner casing having a substantially imperforate portion at one end which is adapted to deflect a fluid after it passes through the inlet opening so that it contacts with the wall, said wall being perforated to permit the passage of the fluid into and out of the inner casing, a substantially imperforate portion at the other end of the inner casing, and means for obstructing the space between the outer casing and the said wall of the inner casing at a point intermediate of the wall, whereby the fluid is caused to pass into the inner casing on one side of the ob-

struction and to pass out of the inner casing at the other side of the obstruction.

4. A silencer comprising an outer casing 35 having an inlet opening and an outlet opening, an inner casing transversely divisible into two shells containing filling material and placed base to base, each of the shells having substantially imperforate portions at the remote ends thereof and being perforated along a side wall, said inner casing being spaced from the outer casing along the major portion thereof, and an obstruction adjacent the bases of the shells for causing 40 a fluid passing through the outer casing to enter the inner casing through one of the shells and pass from the inner casing through the other shell.

5. A silencer comprising an outer casing 50 having an inlet opening and an outlet opening, an inner casing transversely divisible into two approximately conical perforated shells having at their bases annular enlargements forming an obstruction adapted to 55 engage the outer casing, the remainder of said shells being spaced from the outer casing and having substantially imperforate portions at the apices thereof, whereby a fluid passing through the outer casing will 60 enter the inner casing at one side of the enlargements and pass therefrom at the other side of the enlargements.

NICHOLAS STRAUSSLER.
